UNITED STATES PATENT OFFICE.

JOHN HENRY ASTRUCK, OF NEW YORK, N. Y.

DESIGN FOR A BASE-PLATE FOR STANDS OR SIMILAR ARTICLES.

41,686.

Specification for Design.

Patented Aug. 15, 1911.

Application filed April 8, 1911. Serial No. 619,911. Term of patent 14 years.

To all whom it may concern:

Be it known that I, JOHN HENRY ASTRUCK, a citizen of the United States, residing at New York city, county and State of New York, have invented a new, original, and ornamental Design for Base-Plates for Stands or Similar Articles, of which the following is a specification, reference being had to the accompanying drawing, forming part thereof.

The figure is a perspective view of a base plate for stand or similar articles, showing my new design.

I claim:

The ornamental design for a base plate for stand or similar articles, as shown.

JOHN HENRY ASTRUCK.

Witnesses:

FRANK V. BRIESEN,
KATHERYNE KOCH.
